GAME PUTTING TARGET

Remo E. Lindner, 3311 N. 13th St., Sheboygan, Wis.

Filed Dec. 5, 1963, Ser. No. 77,680

Term of patent 3½ years

(Cl. D34—5)

The single figure is a perspective view of a game putting target embodying my new design. The surfaces not visible are plain.

The dominant features of my design reside in those portions thereof shown in solid lines.

I claim:

The ornamental design for a game putting target, as shown and described.
